FOREIGN PATENT DOCUMENTS

WO WO 03053101 A1 6/2003

Primary Examiner—T. Chase Nelson
Assistant Examiner—Ania K Dworzecka(74) *Attorney, Agent, or Firm*—Fay Sharpe LLP; Brian E. Turung(57) **CLAIM**

The ornamental design for a towel warming device, as shown and described.

DESCRIPTION

FIG. 1 is a perspective view of a towel warming device showing my new design;

FIG. 2 is a front elevation view of a towel warming device showing my new design;

FIG. 3 is a top plan view of a towel warming device showing my new design;

FIG. 4 is a side elevation view of the towel warming device showing my new design; and,

FIG. 5 is a back elevation view of the towel warming device showing my new design.
